UNITED STATES PATENT OFFICE.

GEORGE W. SANFORD, OF THOMASTON, CONNECTICUT, ASSIGNOR OF ONE-THIRD TO PATRICK McCAIN, OF SAME PLACE.

WICK-RAISER.

SPECIFICATION forming part of Letters Patent No. 298,779, dated May 20, 1884.

Application filed January 22, 1884. (No model.)

To all whom it may concern:

Be it known that I, GEORGE W. SANFORD, of Thomaston, in the county of Litchfield and State of Connecticut, have invented certain new and useful Improvements in Wick-Raisers; and I do hereby declare the following to be a full, clear, and exact description of the invention, such as will enable others skilled in the art to which it appertains to make and use the same.

My invention relates to an improvement in wick-raisers, the object being to provide a device of this character which shall be adapted to raise the wick evenly by allowing each of the corners to be slightly raised independently of the other, and also to provide improved means or bearings for securing the shafts carrying the raising-disks to the wick-tube. A further object is to provide an improved wick-raiser which shall be simple and economical in construction, and at the same time durable and efficient in use; and with these ends in view my invention consists in certain novel features of construction and combinations of parts, as will be hereinafter described, and pointed out in the claim.

In the accompanying drawings, Figure 1 is a view in perspective of my improved wick-raiser. Fig. 2 is a vertical sectional view thereof; and Fig. 3 is a sectional view of the same, taken on the line *x x*.

A represents a flat wick-tube, and B the base of the burner. The tube A is provided near its lower end with the vertical elongated slots C, formed near the outer edges of the tubes. In these slots fit the toothed disks D, rigidly secured to the shafts E near their ends.

To the wick-tube A, between the slots C, is soldered or otherwise rigidly secured the plate F, which is laterally fluted, as shown at G, forming a bearing for the inner ends of the shafts E, which latter also pass through perforations or holes formed in the base B, and

are provided on their outer ends with the disks H. By this construction it is evident that each raiser may be operated independently of the other, thereby raising one edge of the wick without disturbing the other. By these means, when the wick burns unevenly, one corner may be raised or the higher corner lowered, as desired, instead of extinguishing the light and trimming the wick; or, when desired, the raisers may be operated simultaneously, thereby evenly raising or lowering the wick. Again, by soldering the bearing-plate F on the outer side of the wick-tube, an even and unbroken bearing-surface is afforded the wick on the inner side of the wick-tube.

I am aware that it is not broadly new to regulate a wick by means of a spur-wheel secured to a hollow shaft and a second spur-wheel secured to a smaller shaft, which latter passes longitudinally through the hollow shaft, and hence I make no claim thereto.

My invention possesses advantages over the above construction, in that it is more simple in construction and can be manufactured at a reduced cost.

Having fully described my invention, what I claim as new, and desire to secure by Letters Patent, is—

The combination, with a wick-tube provided with elongated slots, of a bearing secured to said tube between the slots, shafts passing through the base of the burner, and having their inner ends journaled in said bearing, and toothed disks secured to the shafts and fitting in said slots, substantially as set forth.

In testimony whereof I have signed this specification in the presence of two subscribing witnesses.

GEORGE W. SANFORD.
